UNITED STATES PATENT OFFICE.

HALVOR OLSEN EIANE, OF SAN DIEGO, CALIFORNIA.

AEROPLANE.

1,044,635.

Specification of Letters Patent.

Patented Nov. 19, 1912.

Application filed January 24, 1912. Serial No. 673,459.

To all whom it may concern:

Be it known that I, HALVOR OLSEN EIANE, a citizen of the United States of America, and a resident of the city of 5 San Diego, in the county of San Diego and State of California, have invented certain new and useful Improvements in Aeroplanes, of which the following is a specification.

10 My invention has for its primary object to provide means acting automatically to maintain the lateral balance of an airship.

15 A further object resides in the provision of a novel sub-frame or alighting gear of novel construction.

20 Other objects will be set forth as my description progresses, and those features of construction, arrangements and combinations of parts on which I desire protection, succinctly defined in my annexed claims.

25 Referring to the accompanying drawings wherein like numerals of reference indicate like parts throughout: Figure 1 is a fragmentary top plan of an aeroplane embodying my invention. Fig. 2 is a fragmentary cross-section illustrating more particularly the operator's controlling mechanism for maintaining the machine on its course. Fig. 3 is a fragmentary side elevation. Fig. 4 30 is a front elevation of the alighting gear, and Fig. 5 is a vertical cross-section taken on line 5—5 of Fig. 1.

35 Referring to the drawings by numerals of reference, 7 indicates two sail or sustaining planes mounted on the machine frame 8 on opposite sides and rearwardly of vertical planes 19, which latter are adapted to be operated by air currents for warping planes 7 to thereby maintain the lateral balance 40 of the airship, as hereinafter more fully set forth. Vertical planes 19 are of flexible construction so that they will bow or be forced to a concave formation by the air, thereby affording a better purchase for the

45 air, as will be readily understood. As now considered, these vertical planes 19 comprise frame sections 19', 19'' pivotally connected one to the other, as at 19^a. Plane sections 19' are pivotally connected with 50 respective frame uprights 8' while sections 19'' are provided with apertured lugs 19^b freely engaged with guides 20 of frame 8 to permit of the plane sections 19'' sliding

and swinging thereon, as indicated by dotted lines in Fig. 1. Springs 21 engage lugs 19^b 55 and yieldingly hold the planes 19 in their normal position.

Reference numeral 50 indicates a runner fixed to depending frame connections 51, and 52 indicates a forwardly disposed pair 60 of supporting wheels, yieldingly connected with frame 8 and normally projecting below said runner to absorb the shock incident to the alighting of the machine.

In my present construction, I journal 65 wheels 52 on stub axles 54, which are pivotally connected to main supports 56, pivoted at 53 and 56' to frame 8 for swinging of axles 54 in an outward and upward direction, as more clearly shown in Fig. 4. Acting 70 conjointly with supports 56 are braces 57, conveniently formed of telescopic sections. The outer or tubular brace sections are slotted longitudinally for reception of lugs 57' of the inner sections, which lugs 75 engage springs 59 seated against suitable end shoulders 57'' of the said tubular brace sections. Braces 57 are pivoted to frame 8 and have axles 54 fixed to their outer end portions. 80

I have shown my vertical planes 19 and alighting gear, hereinbefore described, in connection with the airship construction forming the subject matter of my application, Serial No. 651,473, filed September 26, 85 1911. In such construction, the sail or sustaining planes 7 are provided with pivots 9 journaled on frame 8 whereby said planes can be moved to different angles with respect to the horizontal line. 90

11 indicates a horizontal rudder, fixed to a shaft 12 which is journaled in suitable bearings at the extreme rear portion of frame 8.

Reference numeral 14 indicates a vertical 95 rudder hinged on a support 15 fixed to and projecting upwardly from shaft 12.

At the forward end portion of frame 8 I provide a pilot-plane 16, the same being normally disposed in a horizontal position and 100 supported by pivots 15, whereby it can be swung against tension of suitable springs 18.

Reference numeral 13 indicates a link 105 pivotally connected with plane sections 19' (see Fig. 1), whereby said plane sections are maintained in parallel relation irrespec-

tive of their sidewise movement and both connected for simultaneous movement in a common direction.

Reference numeral 24 indicates flexible connections secured to vertical planes 19, as shown, and each leading through suitable idler pulleys to a suitable point on the outer end edge of the adjacent sail or sustaining plane 7, whereby when a plane 19 has its intermediate portion moved laterally in response to air currents, the connected plane 7 will have its outer end or tip portion drawn downwardly. Such coöperation of said planes 19 and the tip ends of sail planes 7 is possible, however, only when sail planes 7 are set in a horizontal position since rope 24 may be taut only when sail planes are in such horizontal position.

33 is a fixed sail plane disposed to extend across and from each side of frame 8 at the underside thereof and by which it is supported at a suitably slight fixed angle with respect to a horizontal line, and 34 is also fixed sail plane disposed on and secured to the top of frame 8 between the two sail planes 7 where it is set at a suitably slight angle with respect to a horizontal line, permanently.

Reference numeral 27 indicates a steering wheel, fixed to a shaft 28 whose lower end portion is connected by a universal joint 29 with a shaft 30, journaled in bracket 32 and provided with a drum 35 to which cords 36 are secured. These cords take over respective direction pulleys 43 spaced lengthwise on the forward edge portion of plane 33 and thence upward over respective pulleys 43', provided on the rear edge portions of sail planes 7, and finally back over the said pulleys 43 to a ring 45 to which the ends of all of the cords 36 are secured, whereby when wheel 27 is rotated, the sail planes will be moved in unison to an angular position. Shaft 28 extends upwardly through a slot in the top portion of a yoke 37 whose arms are hinged at their lower ends on studs 39, fixed to frame uprights 40, by which construction, shaft 28 may be moved forwardly and backwardly or to either side. On shaft 28 adjacent to the yoke 37, is a loose collar 41 to which is fastened cords or the like for operating the vertical rudder 14. The horizontal rudder 11 may be operated by ropes 42, extending between the centers of the vertical portions of yoke 37 and said rudder 11, whereby a forward or backward movement of shaft 28 will adjust said rudder.

Reference numeral 44 indicates pedals, 60 fulcrumed on frame studs 39 and having cords 46 connected therewith and to ring 45, whereby a movement of one of said pedals 44 in a downward direction will cause ring 45 to move sidewise and effect a downward adjustment of the rear end portion of one

plane 7 and release the other plane for adjustment in a relatively opposite direction by the air.

Having thus described my invention what I claim as new, and desire to secure by Letters Patent of the United States of America, is:—

1. In an aeroplane, a supporting frame, a vertical flexible plane connected at its opposite end portions to said frame, the connection between one end portion of said plane and said frame permitting of the former sliding on the latter, a sustaining plane on said frame, and a connection between said sustaining plane and said vertical plane for effecting a warping of the sustaining plane by movement of the intermediate portion of said vertical plane crosswise of the frame. 75

2. In an aeroplane, a supporting frame, a sustaining plane on said frame, a vertical plane formed of pivoted sections, one of which is pivoted to said frame, means slidably supporting the other vertical plane section on said plane, and a flexible connection between said vertical plane and said sustaining plane for effecting warping of the latter through the action of air currents crossing the path of the machine. 90

3. In an aeroplane, a supporting frame, a sustaining plane on said frame, a vertical plane formed of hinged sections, one of which is pivotally connected with said frame, means slidably guiding the other section of said vertical plane on said frame, means yieldingly holding said vertical plane sections in line, and an operative connection between said vertical plane and said sustaining plane, whereby the latter will be warped through the action of air currents crossing the path of the machine. 100

4. In an airship, means for maintaining the lateral balance of the ship comprising a vertical plane supported thereon for movement of its intermediate portion beyond its end portions in a direction laterally of the ship by the air, and a substantially horizontal plane connected for adjustment by said vertical plane. 110

5. In an airship construction, means for maintaining the lateral balance of the ship comprising a plurality of vertical planes spaced laterally of the ship and mounted thereon for movement of their intermediate portions laterally beyond their end portions by the air, means connecting the intermediate portions of said vertical planes for simultaneous movement in a lateral direction, and a substantially horizontal plane connected for adjustment by said vertical planes. 115

6. In an airship construction, means for maintaining the lateral balance of the ship comprising a vertical plane supported on the ship for movement of one end portion toward and from the other, whereby its in- 120

termediate portion can be moved by the air laterally beyond its end portions, and a substantially horizontal plane connected for adjustment by said vertical plane.

5 7. In an airship construction, means on the ship for maintaining the balance thereof comprising a vertical plane formed of articulated sections supported one forwardly of the other for swinging in a
10 common direction by air currents crossing

the path of the ship, and a second plane connected with said first plane for adjustment thereby.

Signed at Vallejo, California, this 12 day of January 1912.
